UNITED STATES PATENT OFFICE.

SAMUEL ARRINGTON, OF NEW YORK, N. Y.

AEROPLANE SAFETY DEVICE.

1,408,062.

Specification of Letters Patent. Patented Feb. 28, 1922.

Application filed August 1, 1921. Serial No. 488,780.

To all whom it may concern:

Be it known that I, SAMUEL ARRINGTON, citizen of the United States, residing at New York, in the county of New York and State 5 of New York, have invented certain new and useful Improvements in Aeroplane Safety Devices, of which the following is a specification.

This invention relates to parachutes intended more particularly for use in connection with aeroplanes, each aeroplane being preferably equipped with a number of the parachutes.

The invention has for an object to provide 15 a novel type of parachute, and further, to provide a series of parachutes of which one is substantially at the centre of gravity of the aeroplane, the different parachutes being so arranged that the said central parachute 20 will open in advance of the others.

For further comprehension of the invention, and of the objects and advantages thereof, reference will be had to the following description and accompanying drawings, and 25 to the appended claims in which the various novel features of the invention are more particularly set forth.

Fig. 1. of the drawings is a diagrammatic plan view of an aeroplane equipped with a 30 number of my improved parachutes, the latter being indicated in open position.

Fig. 2. is an elevation, with parts broken away, of one of the parachutes.

Fig. 3. is a vertical section on the line 35 3—3 of Fig. 2.

Fig. 4. is a horizontal section on the line 4—4 of Fig. 3.

Fig. 5. is a fragmentary vertical section 40 showing particularly the means whereby opening of the central parachute causes the others to open, this view being taken on the line 5—5 of Fig. 4.

In Fig. 1. of the drawings the reference 45 numeral 10 indicates the body of a biplane and 11 the top plane. Upon this top plane 11, is mounted over the body 10, a relatively large parachute indicated in general at P. Grouped around this central parachute are four smaller ones indicated generally at p, 50 two of these being mounted adjacent the ends of plane 11, and two on the body 10 one in front and one in the rear of such plane.

Each of these parachutes comprises a central standard or post 15 projecting rigidly 55 upward from a bracket element 16, the lat-

ter being adapted to be secured to the part on which the parachute is mounted. To the upper end of post 15 is fixed a head 17 to which a number of metal ribs 18 are pivotally attached at one end. These ribs have a suitable cloth member 19 secured thereon. Hinged at one end to the metal ribs 18, approximately midway between the ends of the latter, are struts 20 whose opposite ends 60 connect pivotally to a collar 21 slidable on the post 15. Fixed at opposite ends to the head 17 and collar 21 is a tension spring 22, while an expansion spring 23 bears between the collar and the bracket 16, these springs 65 70 surrounding the post 15 and both acting on the collar 21 to open the parachute.

The parachute is locked in its closed position by means of a latch 25 fulcrumed as at 26 to the bracket 16 and having a hooked 75 upper end adapted to engage in an eye member 27 carried by the collar 21. The latch 25 is adapted to be released by means of a solenoid 28 suitably mounted in the bracket 16 and having its plunger connected 80 to said latch. To close the parachute I provide a rope 30 which is connected to the collar 21 and passes downward through suitable guides 31 to a drum 32 fixed on a shaft 33 mounted in the bracket 16, one end of the 85 shaft 33 presenting a square socket 34 adapted to receive a suitable crank for turning the shaft 33. Pivoted to the bracket 16 at 37 is a second latch 38 which has a hooked end adapted to engage in a suitable socket in the 90 end of the drum 32 to hold the latter against rotation. A tail-piece 25' on latch 25 bears against latch 38. The parachutes may be braced by means of guy ropes 40 connected 95 to the tops of the posts 15.

The different parachutes, as so far described, are all alike. In addition the central parachute P carries a circuit closing device illustrated in Figs. 4 and 5 and adapted to close a circuit through the solenoids of the 100 other parachutes when the central one has reached, or nearly reached, open position. As here shown an angular contact arm 45 is pivoted in the collar 21 and is pressed by a spring 46 against the post 15. Seated in 105 the latter, at the proper height, is a contact 47 adapted to be engaged by the contact 45. A wire 48 connects, by means of the angular element 49, to the contact arm 45, while a wire 50 leads upward through the post 15 110 from the contact 47.

The electrical connections are shown in

Fig. 1, the wire 48 being connected to one side of a battery 52, while the wire 50 is branched as at 53 to the solenoids of the parachutes *P*, returns 54 from the said sole-
 5 noids leading back to the other side of battery 52. The solenoid of parachute *P* is placed in a separate circuit, indicated generally at 55 and controlled by a hand switch 56 placed in easy reach of the pilot.
 10 In the use of the device, when the para-
 chutes are to be opened the pilot closes key 56, energizing the solenoid of parachute *P* and releasing the latch 25 from the collar 21, while at the same time the tail-piece
 15 25' of this latch bears on the latch 38 and frees the drum 32. The parachute is then opened by springs 22 and 23 when contact arm 45 on collar 21 engages contact 47 on post 15, the solenoids of the other para-
 20 chutes are energized and the latter caused to open.

Having thus described my invention what I claim as new and desire to protect by Letters Patent of the United States is as
 25 follows:

1. In an aeroplane, a parachute located above the centre of gravity of the aeroplane, and a series of parachutes grouped around said parachute, and means for first opening all of said parachutes, the means for opening the last named series of parachutes being controlled by the opening of the first parachute.
2. In an aeroplane, a parachute located above the centre of gravity of the aeroplane, and a series of parachutes grouped around said first parachute, and means for first opening said first parachute and then the other parachutes, said means including mem-
 30 bers adapted for automatic actuation when the first parachute opens.
3. In an aeroplane, a parachute located above the centres of gravity of the aeroplane, and a series of parachutes grouped around said first parachute, and means for first opening said first parachute and then the other parachutes, said means including springs for opening said parachutes, latches holding said springs in closed position, sole-
 45 noids for releasing the latches, a hand switch for closing the circuit to the solenoid

of the first parachute and a switch closed by opening movement of the first parachute for closing the circuit to the solenoids of the other parachutes.

55

4. A parachute comprising a post, a para-
 chute proper mounted on said post, a collar slideable on said post and adapted to open and close said parachute by movement there-
 along, springs urging said collar to posi-
 60 tion with the parachute open, a latch engag-
 ing said collar to hold the parachute closed, and a solenoid for releasing said latch, a
 rope attached to said collar, a winding drum
 for said rope, and a latch holding said 65
 drum against rotation, said first latch being
 adapted to release said second latch when
 moved by said solenoid.

5. A parachute comprising a post, a para-
 chute proper mounted on said post, a collar 70 slideable on said post and adapted to open and close said parachute by movement there-
 along, springs urging said collar to position, with the parachute open, a latch engaging
 said collar to position with the parachute 75 closed, and a solenoid for releasing said
 latch, a rope attached to said collar, a wind-
 ing drum for said rope, and a latch holding
 said drum against rotation, said first latch
 having a tail-piece adapted to engage and re-
 lease said second latch when the first latch
 is released.

6. In an aeroplane, a parachute located above the centre of gravity of the aeroplane, a series of parachutes grouped around the 85 first parachute, said first parachute comprising a post, a collar slideable on said post and adapted to open and close said para-
 chute by movement therealong, latches holding said series of parachutes against opening 90 movement, solenoids controlling said latches, a fixed contact member on said post, a con-
 tact member on said collar adapted to en-
 gage the fixed contact member when the
 first parachute reaches open position, said 95 contact members being adapted to close a circuit through said solenoids when in en-
 gagement with one another.

In testimony whereof I have affixed my signature.

SAMUL ARRINGTON.
